VOLUME COMPRESSOR FOR CARBON
MICROPHONESJohn C. O'Brien, Rochester, N. Y., assignor to
General Railway Signal Company, Rochester,
N. Y.

Application July 16, 1946, Serial No. 684,062

7 Claims. (Cl. 179—1)

1

This invention relates to audio volume compressor organizations, and more particularly pertains to the provision of a regulator organization for governing the output of an audio amplifier having associated therewith a carbon type microphone.

It is, of course, generally understood that the audio frequency output of a microphone must be amplified in order to suitably act upon the modulating stages of a radio transmitter or for the control of recorders, and the like. However, in both cases, it is desirable to limit the variation in the volume of the audio output of the amplifier even though the input to the microphone may vary over a wide range. In the case of radio transmission, such a volume compression is desirable to prevent over-modulation which would cause distortion. Similarly, in making recordings, there are limits to the recording channel regardless of the type of recorder employed.

In view of the above considerations, it is proposed in accordance with the present invention to provide an audio volume compressor organization suitable for use with a carbon type microphone especially adaptable to portable equipment.

Generally speaking, and without making any attempt to define the exact nature or scope of the invention, it may be stated that the compressor organization contemplated includes two electronic tubes one of which acts as an amplifier and the other of which acts as a regulator tube to govern the current through the microphone. This regulator tube by decreasing the current flow through the microphone upon an increase in the output of the amplifier tube acts to decrease the audio frequency output of the microphone at the input of the amplifier. In this way, the microphone is limited in the extent of the volume that it can supply to the amplifier even though there may be wide variations in the input supplied to the microphone.

A further feature of the present invention is to organize the amplifier and regulator tubes in such a way as to provide control over the bias of the grid of the amplifier in accordance with the output of the amplifier. This acts to vary the amplification factor of the amplifier tube in a manner to further compress the volume variations with respect to the local carbon microphone. Also, this compression characteristic effected by variation of the amplification factor of the amplifier can be used independently of the current control of the local microphone to compress the volume variations of an audio input supplied from a

2

remote point over line wires (or other source of audio input).

Other objects, purposes and characteristic features of the present invention will be in part obvious from the accompanying drawings, and in part pointed out as the description of the invention progresses.

In describing the invention in detail, reference will be made to the accompanying drawing which illustrates a volume compressing organization in a simplified diagrammatic manner as one embodiment of the present invention.

For the purpose of simplifying the illustration and facilitating in the explanation, the various parts and circuits constituting the embodiment of the invention have been shown diagrammatically and certain conventional illustrations have been employed, the drawing having been made more with the purpose of making it easy to understand the principles and mode of operation than with the idea of illustrating the specific constructions and arrangement of parts that would be employed in practice. Thus, the various devices are illustrated in a conventional manner, and various conventional symbols are used to indicate the devices, wiring connections, batteries or other sources of electric current and the like.

With reference to the single figure of drawing, an audio volume compressor organization is shown as including an amplifier tube T1 and a regulator tube T2 having associated resistors, capacitors, wiring connections and the like so arranged as to supply an audio output at terminals 5 and 6, which audio output may be connected to another amplifier stage or may be connected directly to the reactance stage of a frequency modulated transmitter such as shown in my prior application, Ser. No. 612,600, filed August 25, 1945, now Pat. No. 2,441,504, dated May 11, 1948. On the other hand, the output terminals 5 and 6 may be connected to the modulating stage of an amplitude modulated radio transmitter, or may be connected to the input terminals of any suitable recorder mechanism. It should be understood that the present invention may be employed in various connections, but is especially adaptable to portable organizations where a simple but effective volume compressor is desired for use in connection with a microphone of the carbon type.

The amplifier tube T1 and regulator tube T2 have been shown as independent tubes having their cathodes connected together and providing a circuit to a suitable ground connection through a microphone of the carbon type. However, these two tubes may be combined in a single en-

velope and have a common cathode connection, but for convenience in the circuit diagram the tubes have been shown in separate envelopes. The cathode heaters for the tubes T_1 and T_2 are assumed to be continuously energized from a suitable source. The plate supply has been indicated as a battery designated B having its negative terminal connected to ground and its positive terminal connected through a resistor R_1 to the plate of the regulator tube T_2 . The plate supply B is also connected through resistors R_2 and R_3 to the plate of the amplifier tube T_1 . The audio frequency output of the amplifier tube T_1 is connected through a condenser C_1 and resistor R_4 to ground. The potential drop across the variable resistor R_4 supplies the output to terminals 5 and 6.

A feed-back connection is provided to the grid of the regulator tube T_2 by the condenser C_2 , and a grid leak resistor R_6 is connected between such grid and ground. A resistor R_5 provides a connection between the grid of the regulator tube and the control grid of the amplifier tube T_1 , while a condenser C_3 provides a connection to ground from the control grid of the amplifier tube T_1 for audio frequencies.

A transformer TF is shown having its secondary winding connected between the grid of T_1 and the by-pass condenser C_3 while its primary winding is indicated by suitable legend as connected to a remotely located microphone over a suitable line circuit.

A condenser C_4 is provided to by-pass audio frequencies from the plate of the regulator tube T_2 to the cathode for reasons later explained.

With the above general discussion of the structure of the organization, one possible theory of operation of the organization will be given as a guide to the practice of the invention.

With reference to the drawing, it will be apparent that the microphone is located in the plate-cathode circuit of both the amplifier tube T_1 and the regulator tube T_2 . Since the microphone is of the carbon type, it provides a variable resistance in the cathode circuits of the tubes T_1 and T_2 to act as a variable bias for the grids of the respective tubes.

The variations in resistance of the microphone also acts to vary the voltage in the plate circuit of the tube T_1 , but since the audio alternating voltage output of such a microphone is relatively small, it will be appreciated that the effect of the microphone is mainly on the grid circuit of this tube T_1 . Thus, the tube T_1 may be conveniently considered as a cathode driven or modulated amplifier since the action of the microphone is upon both its grid and plate circuits.

It will be apparent that the same audio frequency voltages appearing across the condenser C_1 and resistor R_4 also appear across the resistors R_2 and R_3 in series with the condenser C_4 . Thus, a portion of the audio frequency output of the amplifier tube T_1 is fed to the control grid of the tube T_2 through a condenser C_2 by a connection made between the resistors R_2 and R_3 . This audio frequency supplied to the grid of the regulator tube T_2 is rectified by this grid and builds up a negative bias across the grid leak resistor R_6 . Since the grid leak resistor R_6 tends to provide a drain for such negative bias, the actual value of negative bias depends upon the value of the audio signal output of the amplifier tube T_1 .

The negative bias built up across the grid leak resistor R_6 is also supplied to the control grid

of the amplifier tube T_1 through the decoupling resistor R_5 and with a by-pass condenser C_3 . In other words, the negative bias supplied to the control grid of the regulator tube T_2 is also supplied to the control grid of tube T_1 with only a slight lag due to the capacity of condenser C_3 and the resistance value of the resistance R_5 .

It will be noted that the plate supply battery B is fed directly to the plate of the regulator tube T_2 including only the resistor R_1 , whereas the plate circuit of the amplifier tube T_1 also includes resistors R_2 and R_3 . For this reason, the plate-cathode current of the amplifier tube T_1 is relatively small compared to the plate-cathode current of the regulator tube T_2 . These currents reach their combined maximum value in flowing through the microphone when there is no audio input to the microphone. Thus, any message spoken into the microphone, or sound otherwise produced, causes an audio signal to be applied to the grid of the amplifier tube T_1 which audio signal is amplified in accordance with the then existing bias on the control grid of that tube. This output of the amplifier T_1 is fed to the filter network associated with the control grids to produce a negative bias of a value depending upon that strength signal within a time factor determined by the relative sizes of the condensers and resistors involved. It might be noted that the time delay response in the change in bias on these tubes is preferably in the order of a fraction of a second, such as $1/20$ of a second or the like, so that variations in volume supplied to the microphone will result in being compressed if such variations exist longer than the time delay inherently built into the organization, but will not be erased if the variations are relatively shorter. This is a desirable characteristic so as to retain a reasonable amount of the inflections of the voice and the emphasis of the words spoken to thereby give a suitable degree of naturalness to the reproduced signal.

It will be apparent that any increase in the negative bias on the control grid of the regulator tube T_2 results in a decrease of its plate current which decreases the current flowing through the microphone. Such decrease in current in the microphone directly affects its input with respect to the control grid of the amplifier tube T_1 . In other words, the stronger the audio frequency signal the greater is the decrease in the current through the microphone. This acts to compress the variations in intensity of audio signal by governing the current through the microphone.

The condenser C_3 and resistor R_5 act as a filter combination to prevent audio frequency signal from being applied to the control grid of the amplifier tube T_1 , since such an application of audio frequency signal would cause regeneration and distortion of the output of the amplifier. The amplifier tube T_1 can to advantage be of the variable-mu or remote cut-off control grid type so that an increase in the negative bias on such control grid will cause a decrease in the amplification factor of the tube. In this way the increase in negative bias supplied by the circuit organization to the two control grids acts to cause compression both by a regulation of the current through the microphone and by a decrease in the amplification factor of the amplifying tube T_1 . However, in this regard it should be noted that the major portion of the regulation is supplied by the control of the current through the microphone and that the variable-mu characteristics of the amplifier tube act as sup-

plementary to the desired characteristics of the organization.

In this connection, it should be noted that the control grid of tube T1 can be connected directly to ground if the compression due to the control of the amplification factor of tube T1 is not desired, since the compression given by the regulator tube T2 is substantial and provides the major portion of the regulation of the output with respect to the local carbon type microphone. However, in the present organization, it is desired to also provide for an input to the amplifier tube T1 from a remotely located microphone.

The output of this remote microphone is connected over a suitable line circuit and through a transformer such as TF into the grid circuit of the tube T1 without in any way affecting the operation of the local microphone. The remote microphone, thus connected, may have its variable input governed in accordance with the variable-mu characteristics of the tube T1 but not by the regulator tube T2. However, this is entirely feasible because it is contemplated that such remote microphones are usually located in an office or studio where the range of volume variations will be less than that which may occur in connection with the portable microphone local to the compressor organization. This is especially true where the organization is employed in connection with railroad communication systems in which case the remote microphone will probably be in an office used by the same operator rather consistently, whereas the local microphone may be adjacent to the trackway or in a locomotive cab and used by many different trainmen under varying conditions.

The volume compressor organization provided in accordance with the present invention is thus very useful in train communication systems since it is an aid in reducing background noise and interference. For example, when the background noise is very high, the trainman will speak very loudly into the microphone in an effort to overcome the local background noise. In so doing, the compressor action takes place limiting the amplification of the organization with respect to the voice message spoken into the microphone. In so doing, it actually reduces the amplification to such an extent that the background noise is not reproduced to any substantial degree, whereas the voice message is reproduced with just a slightly increased volume. In other words, the use of the compressor organization of the present invention acts to eliminate background noises to the extent that they are compensated for by the trainman in regulating his voice in accordance with such background noises.

The condenser C4 is provided to by-pass audio frequencies between plate and cathode of the tube T2 so that any audio frequencies which might be produced by the feed-back connection to the control grid of the tube T2 will be suppressed and not cause regeneration in the circuit organization. For the same reason, the decoupling resistor R1 is provided to keep the audio frequency of the plate circuits from being fed back to the grid circuit of the tube T1 via the plate supply battery B.

In an organization of this type, it is necessary that the plate supply potential be held substantially constant so as to be able to properly adjust the different values in the compressor organization to their operating points for giving the desired operation. The usual battery, such as designated B, will supply a suitable constant po-

tential, but it should be understood in actual practice suitable power pack will probably be employed, and in such a case it is desirable that the power supply organization be of such a character as to give a substantially constant plate potential. This can be accomplished by numerous expedients such as by the use of a voltage regulator gas tube.

It should be understood that the coefficients of the tubes T1 and T2 may be suitably chosen in accordance with the requirements of the particular application in practice to which the compressor organization is to be applied. If the remote input is not to be employed, then it is apparent that the variable-mu characteristics of the tube T1 are not necessary. On the other hand, if it is desired to provide considerable compression for the remote input as well as additional compression for the local microphone input, then the tube T1 should be of a remote cut-off type.

Having described an audio volume compressor organization as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention.

What I claim is:

1. In an audio volume compressor organization, a carbon microphone, an amplifier connected to be cathode modulated by said microphone, a regulator tube having its cathode-plate circuit also connected through said microphone, and means governing the output of said regulator tube to decrease the current through said microphone when the output of said amplifier increases to thereby compress the audio variations in volume as supplied to said microphone.
2. In an audio volume compressing organization, a carbon microphone, an amplifier stage and a regulator stage both having their cathode-plate circuits connected through said microphone, whereby said microphone can provide an audio component for the grid of said amplifier, means for causing the plate current of said amplifier to be relatively small compared to the plate current of said regulator, and feed back circuit means connected from the plate of said amplifier to the grid of said regulator for increasing the negative bias on said regulator as the output of said amplifier increases to thereby decrease the audio output of said microphone into the grid cathode circuit of said amplifier and thereby compress the variations in volume supplied to said microphone.
3. In an audio volume compressing organization, an amplifier having an audio input supplied by a carbon microphone, the output of said microphone varying in accordance with its current supply, means including a regulator stage for controlling the current through said microphone, and means for governing the output of said regulator stage in accordance with the output of said amplifier to cause a decrease in microphone current as the output of said amplifier increases.
4. In an audio volume compressor organization, a carbon type microphone, an amplifier connected so as to be cathode driven by said microphone and having a variable-mu control grid, a regulator tube having its cathode-plate circuit

connected through said microphone and having a control grid to govern the cathode-plate circuit current; a feed-back circuit for supplying a portion of the output of said amplifier to the control grid of said regulator tube; a grid-leak filter circuit connected to the control grid of said regulator tube and also connecting to said control grid of said amplifier with decoupling with respect to audio frequencies whereby the increase of audio input to said microphone causes an increased negative bias to be placed on the control grids of said tubes to thereby decrease the amplification factor of the entire organization both by decreasing the current through said microphone and by decreasing the amplification factor of said amplifier.

5. In an audio volume compressor organization, a carbon microphone and an associated audio amplifier, said carbon microphone supplying an audio input to said amplifier in accordance with the value of current flow through it, and regulator means governed by the output of said amplifier for governing the current flow through said microphone to in turn control the audio input to said amplifier from said microphone.

6. In a volume compressing organization, an audio amplifier including a tube of the variable-mu type having a plate output circuit and a control grid, means for supplying a modulating frequency to said control grid, rectifier circuit means

for rectifying a portion of the output of said amplifier, and circuit means for supplying a variable bias to said audio amplifier from said rectifier circuit means inversely varying with respect to the output of said amplifier, whereby undue variations in the volume of the modulating frequency are compressed by controlling the effective amplification of said audio amplifier.

7. In a volume compressing organization, an audio amplifier tube having a plate and a variable-mu control grid; a transformer coupled audio input circuit for said control grid; a rectifier circuit means connected to the plate of said amplifier for feeding a portion of its output to said rectifier, and filter circuit means having a time constant of a fraction of a second for supplying the output of said rectifier as a negative bias on the control grid of said amplifier, whereby variations in the volume of the audio input to said control grid are compressed to keep the output of said amplifier more nearly constant.
